[57] CLAIM

The ornamental design for a furlined unisex urinal or similar article, substantially as shown and described.

DESCRIPTION

FIG. 1 is a perspective view of a furlined unisex urinal or similar article showing my new design.

FIG. 2 is an end view showing the closed end of a furlined unisex urinal or similar article showing my new design at left in FIG. 1.

FIG. 3 is an end view showing the capped end of a furlined unisex urinal or similar article showing my new design at right in FIG. 1.

FIG. 4 is a top plan view showing the characteristic fur surrounding the elongated hole in a furlined unisex urinal or similar article as shown in my new design in FIG. 1.

FIG. 5 is a right side view of the furlined unisex urinal or similar article as shown in my new design in FIG. 1. The left side not shown is substantially a mirror image of the right side shown.

FIG. 6 is a bottom plan view of the furlined unisex urinal or similar article as shown in my new design in FIG. 1.

FIG. 1.

FIG. 2.

FIG. 3.

FIG. 4.

FIG. 5.

FIG. 6.
